UNITED STATES PATENT OFFICE.

ALBERT R. PRITCHARD, OF ROCHESTER, NEW YORK.

GLOBE-LIFTING DEVICE FOR LANTERNS.

No. 823,078.

Specification of Letters Patent.

Patented June 12, 1906.

Application filed July 21, 1905. Serial No. 270,656.

To all whom it may concern:

Be it known that I, ALBERT R. PRITCHARD, a citizen of the United States, and a resident of Rochester, in the county of Monroe and 5 State of New York, have invented certain new and useful Improvements in Globe-Lifting Devices for Lanterns, of which the following is a specification.

This invention relates to globe-lifting devices for lanterns; and it consists in the apparatus hereinafter described and claimed.

In the drawings, Figure 1 is an elevation of a device embodying this invention. Fig. 2 is an elevation of the lower portion of the 15 same device, showing the parts in a different position. Fig. 3 is a partial view showing the globe-lifting lever and the globe-plate in the same position as in Fig. 1, but from a different point of view; and Fig. 4 shows the 20 same parts and in the same position as in Fig. 2, but from a different point of view.

In the drawings, 1 is the oil-pot.

2 is the gallery.

3 is the burner-cone.

25 4 is the globe-plate.

5 5 are the air-tubes.

6 is the spring-holder for the upper end of the globe 7, actuated by the spring 8. (Shown in dotted lines.) The downward pressure of 30 the spring 8 forces the globe 7 against the globe-plate 4. The tubes 5 are connected at their upper ends to the casing 9, within which the spring 8 and globe-tube 6 are set, and said side tubes are connected at 35 their lower ends to the gallery 2. In order to release the globe and remove it from the lantern, the globe-tube 6 is raised against the force of the spring 8 until the upper end of the globe can be slipped out laterally from 40 said globe-tube. In order to lift the globe and globe-plate for access to light the lantern, lever means are provided for lifting the globe-plate, globe, and globe-tube 6 against the force of the spring 8. For this purpose a wire 10 45 is employed, pivoted at its ends 11 11 in a portion of the frame of the lantern, such as the side tubes 5 5. From the pivotal ends 11 the wire is bent so that there is a middle portion 12 out of the line of the pivots and which 50 middle portion is held to the globe-plate in any suitable manner, such as by the loop 13. The said middle portion 12 is bent or curved so as to pass around the burner-cone 3 and not to make prejudicial contact therewith. At one

end of the wire 10 is formed a handle 14, 55 preferably from the end of the wire itself, the said wire being bent first into the shape of said handle, and then the extremity after the formation of the handle constitutes the pivotal end 11 of said wire at that end thereof. The pivotal end 11 at the end having the handle 14 extends into its perforation and is of such length (see dotted lines, Fig. 1) as to permit it to spring inward and outward in its socket 15 in the side tube. Adjacent 60 to the position of the handle or of the wire 10, adjacent to its pivot 11 on that end, is the catch-plate 16, having the long bevel 17, along which the said adjacent wire slides in passing from the normal position (shown in 70 Fig. 1) to the lifting position, (shown in Fig. 2,) and when in the latter position the said handle-wire springs under a face 18 of said catch-plate. In order to cause an easier operation of the device, the handle proper 14 is bent at 75 an angle of about forty-five degrees to the adjacent arm 19 thereof. The result of this position of the handle 14 is that the tendency is to place the thumb flat against it, and upon pressing, when in that position, the pressure 80 forces the arm 19 out of engagement with the catch-plate 16 or reduces the pressure of such engagement, so that the lifting device is released from its position shown in Fig. 2, or in moving it from the position shown in Fig. 85 1 such movement is made easier. It is obvious that on tilting the lantern from the position shown in Fig. 1 to that shown in Fig. 2 access is given to the burner for lighting or for extinguishing the flame. 90

What I claim is—

1. In a lantern, a lantern-frame comprising side tubes, a globe-plate, a globe, means for holding the globe on the globe-plate, and a globe-lifting device consisting of a bent 95 elastic lever connected to the globe-plate and having ends pivoted in the inner sides of the side tubes out of line with its connection with the globe-plate and also bent between said ends to form an arm adjacent to one of the pivots, and a catch-plate projecting inward from one of the said tubes with which said arm engages. 100

2. In a lantern, a lantern-frame comprising side tubes, a globe-plate, a globe, means for holding the globe on the globe-plate and a globe-lifting device consisting of a bent 105 elastic lever connected to the globe-plate and

having ends pivoted in the inner sides of the side tubes out of line with its connection with the globe-plate and having an arm adjacent to one of the pivots, a catch-plate with which 5 said arm engages, and a thumb-piece on said arm extending outwardly therefrom and at an acute angle thereto, whereby the tendency of pressure on said thumb-piece is to com-

press said bent lever for releasing the arm from the catch-plate or for making easier 10 movement over the same.

ALBERT R. PRITCHARD.
